COMBINED FLOWER PLANTER AND BRACKET THEREFOR

Arthur F. Klingberg, Chicago, Ill., assignor to Bernard
Edward Co., Chicago, Ill., a corporation of Illinois

Application January 24, 1955, Serial No. 34,150

Term of patent 3½ years

(Cl. D35—3)

The figure is a perspective view of a combined flower planter and bracket therefor showing my new design.

I claim:

The ornamental design for a combined flower planter and bracket therefor, substantially as shown.
